United States Patent Office

Des. 190,952
Patented July 25, 1961

190,952

COMBINED RAILING AND WALL BRACKET

Louis Blum, Pittsburgh, Pa., assignor to Blumcraft of
Pittsburgh, Pittsburgh, Pa.

Filed Oct. 18, 1956, Ser. No. 43,396

Term of patent 14 years

(Cl. D13—7)

The single figure is a view in perspective of a combined railing and wall bracket, showing my new design.

I claim:

The ornamental design for a combined railing and wall bracket, as shown.
